UNITED STATES PATENT OFFICE.

HJALMAR HULTGREN, OF FLUSHING, NEW YORK, ASSIGNOR TO EDWARD J. SCHROEDER, OF JERSEY CITY, NEW JERSEY, AND CHARLES A. SCHROEDER, OF BRIELLE, NEW JERSEY.

DESIGN FOR A KEY FOR GAS-COCKS OR THE LIKE.

47,326.

Specification for Design.

Patented May 11, 1915.

Application filed December 23, 1914. Serial No. 878,827. Term of patent 7 years.

To all whom it may concern:

Be it known that I, HJALMAR HULTGREN, a citizen of the United States, residing at Flushing, in the county of Queens and State of New York, have invented a new, original, and ornamental Design for a Key for Gas-Cocks or the like, of which the following is a specification, reference being had to the accompanying drawing, in which the figure is

a plan view of a key displaying my new design.

I claim:

The ornamental design for a key for gas cocks or the like, as shown.

HJALMAR HULTGREN.

Witnesses:

WILLIAM H. BROWN,
M. P. STEVENS.
